STRAIGHT-BAR KNITTING MACHINE

Harry Wilfred Start, Carlton, and Ernest Start,
Wilford, EnglandApplication June 11, 1938, Serial No. 213,252
In Great Britain December 21, 1936

3 Claims. (Cl. 66—128)

This invention relates to improvements in straight-bar knitting machines of the type known as "Cottons", and it refers to the thread carrier bar stop mechanism which is employed when three thread carriers are employed to supply three distinct threads to three distinct groups of the needles, when for example knitting stocking feet with a sole composed of a different class of yarn to the instep. Its object is to provide an arrangement for this purpose which is less complicated than and is free from the defects of existing arrangements.

In order to make work of this character on such machines, one thread carrier is employed to supply a yarn to needles in the middle of the needle bar and knit the instep of a foot for example, and two thread carriers one on each side of the middle carrier, are at the same time employed to supply yarns to groups of needles on the outer side of those needles which are supplied with yarn by the middle carrier, and knit two side strips which form the foot sole.

It will be appreciated, that the middle thread carrier works between two intermediate points in the needle-bar, and the other two thread carriers work between these intermediate points and the selvedges of the work, and that at the intermediate points, the yarn supplied by the middle thread carrier, must overlap one or more of these needles which are supplied with yarn by the side carriers, in order to form secure sutures at the intermediate points. The object of this invention is to provide means whereby a perfect uniform overlap can be made, and which means is free from the defect of existing arrangements. This defect mainly consists of the formation of a pin-hole at the overlap in those courses which are knitted at the same time as the stops are traversed.

According to the present invention, each of the traversing boxes which carry the stops for controlling the movements of the thread carrier bars is provided with a lever stop which is provided with four or more stepped striking faces and is adapted to be raised and lowered and angularly adjusted in order to adjust its several striking faces in the path of a tappet on a thread carrier bar. The other stops are only provided with two striking faces which can be raised and lowering them be adjusted in the paths of tappets on two thread carrier bars. All the stops are raised and lowered by the same mechanism, while the lever stops are angularly adjusted by independent means.

The invention will now be more particularly

described with reference to the accompanying drawings, in which:

Fig. 1 is a sectional side elevation, and

Fig. 2 a front elevation of automatically adjusted thread carrier bar stop mechanism constructed according to our invention.

Fig. 3 is a face view, and

Fig. 4 a side view of the lower end of one of the lever stops which are provided with four or more stepped striking faces in different planes.

Fig. 5 is a perspective view of the lower end of one of the lever stops shown in Figs. 3 and 4.

Like letters indicate like parts throughout the drawings.

In the present arrangement, the thread carrier stops which are employed when knitting the class of work described, are mounted in two boxes A and B which are connected to screw nuts which are mounted on right and left hand threaded parts of a screw shaft C, which is intermittently rotated as usual in the required direction by ratchet wheel and pawl mechanism controlled by studs on a pattern chain. The two boxes A and B are by the action of the screw shaft C, simultaneously moved towards or away from each other as required.

The box A is fitted with two adjustable stops, that is, one which is formed by a plunger E which is carried from the top of the box and extends down below it, and another which is formed by a lever F, which likewise extends from the top of the box down to a point below it, and is slotted midway between its ends where the pivot F' passes through it. The plunger stop E can be raised and lowered, whilst the lever stop F can be both raised and lowered and angularly adjusted about its pivot F'.

The box B is fitted in like manner with a plunger stop G which can be raised and lowered, and a lever stop H which can be both raised and lowered and angularly adjusted about its pivot H' in the same manner as the lever stop F.

The lower end of the plunger stop E in the box A is disposed in the path of an adjustable tappet J' on the thread carrier bar J, and the lower end of the plunger stop G in the box B is disposed in the path of an adjustable tappet K' on the thread carrier bar K. The lower ends of these two stops E and G are stepped, that is, they are each formed with two striking faces, one of which is below and is set back relatively to the other, so that the thread carrier bars J and K when brought to rest by the upper and normal striking faces, can be subsequently moved a little further when the stops are raised to bring the

lower striking faces in action as will be hereinafter described.

The lower ends of both the lever stops F and H are disposed in the path of adjustable tappets 5 L¹ on the same thread carrier bar L, and the lower end of each of these stops is formed as shown in Figs. 3 and 4, with four striking faces a, b, c and d for the tappets L¹ to engage with. The striking faces a and b correspond to the 10 striking faces on the lower ends of the plunger stops E and G, while the striking face c is in the same plane as the striking face b, and the striking face d is set further back than the striking face b. The two striking faces a and b are normally in use, and the striking faces c and d are brought into use by angular adjustments of these 15 lever stops as will be hereinafter described.

The thread carrier bar L, which is fitted with a thread carrier which lays say for example a 20 silk yarn on the needles in the middle of the needle bar is controlled by the lever stops F and H, while the two thread carrier bars J and K which are controlled by the plunger stops E and G are fitted with thread carriers which supply 25 say for example cotton yarns to the needles at the ends of the needle bar, and in drawing each course, these two stops are adapted to stop the cotton yarn carriers when they reach the end needles of the group supplied with yarn by the 30 silk yarn carrier. End stops which are adjustable are also provided in connection with these two bars for stopping the cotton yarn carriers at the edges of the garment.

It will also be appreciated that the stops described are so disposed in the two boxes A and B, that when these boxes are moved closer together, the amplitude of the silk laying carrier will be increased, so that the width of the silk portion of the garment will be increased, whilst the amplitude 35 of the cotton laying carriers will be decreased to a corresponding extent, so that the width of the cotton side strips will be reduced, and that the reverse result will be obtained when the boxes A and B are moved further apart.

When drawing each course, the four stops described will be in their lower or normal positions, but after they have brought the thread carrier bars to rest and the course is being knitted, the four stops are raised, and the thread carriers on 40 the thread carrier bars held by any of these stops are permitted to move a further distance of say two needles in the same direction as formerly, so that when the needles rise again after knitting the course, the yarn from each carrier is supplied 45 to two extra needles outside those on which the last course has just been knitted, and the said yarns start from these points when the next course is drawn. This action effects the necessary overlap of the cotton yarns with the silk 50 yarn on two needles at the two intermediate points in the needle bar, and forms sutures at the junctions of the silk and cotton portions of a garment.

The four stops are raised as described at the 60 proper time every course by the following arrangement.

The upper ends of the plunger stops E and G and the lever stops F and H, are formed with upper ends which engage with a longitudinal rod 65 M¹ disposed above the boxes A and B in which they are disposed. This rod is carried in the free ends of two arms M² secured on a rocking shaft M which is mounted in bearings in the upper ends of arms M³ secured to a fixed shaft 70 M⁴ secured in the fixed frame.

When the boxes A and B are traversed by the screw shaft C, the upper ends of the stops which engage with the rod M¹ described, slide along the said rod and maintain connection therewith, and this rod M¹ is adjusted about the rocking 5 shaft M so as to raise and lower the stops at the proper times, by the following arrangement.

A third arm N on the rocking shaft M which carries the said rod M¹, has its free end connected by a link N¹ to one end of a lever N² which is pivoted at N³ to an arm N⁴ which is secured to the fixed shaft M⁴. The other end of this lever N² is provided with a roller N⁵ which is disposed in the path of cam lifts O which are connected to and reciprocate with the slur cocks 15 O¹, and these lifts O are so disposed that they act upon the lever N² and raise the stops immediately after the drawing of each course has been completed by the continued movement of the slur cocks O¹. The thread carriers are thus permitted to move the required distance in the same 20 direction as when drawing the last course, preparatory to drawing the next course, and thereby effecting the required overlap of the several 25 yarns employed, on the needles.

Further provision has to be made in order to compensate for the traversing movements of the boxes A and B, which take place at intervals in order to vary the amplitude of movement of the three thread carrier bars J, K and L as is 30 required from time to time. This compensation is effected by an angular adjustment of the two lever stops F and H which brings the striking faces c and d on the said stops into operation in place of the normal faces a and b, and the following arrangement is employed for effecting this 35 operation.

A longitudinal rod P which is carried on the free ends of two arms P¹ on a rocking shaft P² disposed just below the shaft M in bearings in the same arms M³ as the latter, passes through slots in the upper end of both lever stops F and H, and the latter are thus always connected to this rod, so that their angular position can always be adjusted by adjusting the rod P, a result 40 which is effected by angularly adjusting the rocking shaft P². For this purpose the rocking shaft P² is fitted with a third arm P³ which is connected by a link P⁴ to a lever S which is adjusted by studs T on a pattern chain U, which 45 may be the same pattern chain which is employed for controlling the mechanism for traversing the boxes A and B.

It thus follows that the lever stops F and H, both of which control the thread carrier bar L 55 and stop it at the intermediate points in the needle bar, are adjusted to bring into action their two extra striking faces c and d which are so disposed as to position the middle thread carrier where it will compensate for the traversing movements of the boxes A and B each time these operations take place. When the boxes A and B are adjusted to widen the middle or silk portion of the garment, the stops F and G must be angularly adjusted to bring the striking faces c and d into action in the course prior to that in which the movement of the boxes A and B is made. On the other hand when the boxes A and B are 60 adjusted in order to reduce the width of the middle or silk portion of the garment, the angular adjustment of the stops F and H must take place in the same course as the boxes A and B are adjusted. This special provision obviates the formation of pinholes in the courses which are 65 70 75

knitted at such times as the boxes A and B are adjusted.

If it is desired to use three middle carriers operating in predetermined succession, as when making silk hose of the type known as "ringless", it is only necessary to add four extra striking faces to the lever stops F and H in order to control the two extra thread carrier bars which are in this case employed, and these four extra striking faces, 10 are disposed in line with tappets on the additional thread carrier bars, in the same relative positions thereto as those employed in connection with the single thread carrier bar previously described.

The adjustable stops E, F, G and H described 15 may be fitted with springs, for returning them to their normal positions, and means are further provided for raising them out of action. For this purpose, an arm R is secured on the end of the rocking shaft M, and this arm is fitted with a 20 pawl R¹ which is adapted to engage with a catch on one of the bearings of the rocking shaft and hold all the said stops in their raised positions.

It will also be understood that further stops 25 may be provided in the boxes A and B which can be put into and out of action by hand.

What we claim as our invention is:

1. In a straight-bar knitting machine having 30 traversing boxes for carrying the stops controlling the movements of the thread carrier bars, the combination with each of the traversing boxes of a lever stop provided with four or more stepped striking faces, a second stop provided with two striking faces, thread carrier bars, tappets on the thread carrier bars, means for raising and

lowering the stops and means for angularly adjusting each of the lever stops in order to adjust its several striking faces in the path of a tappet on a thread carrier bar, substantially as described.

2. In a straight-bar knitting machine having 5 traversing boxes for carrying the stops controlling the movements of the thread carrier bars, the combination with each of the traversing boxes of a lever stop provided with four or more stepped 10 striking faces, a second stop provided with two striking faces, thread carrier bars, tappets on the thread carrier bars, a bar for raising and lowering the stops carried by arms on a rocking shaft, a lever operated by a cam on the slur cock 15 for rocking the shaft, and means for angularly adjusting the lever stops, substantially as described.

3. In a straight-bar knitting machine having 20 traversing boxes for carrying the stops controlling the movements of the thread carrier bars, the combination with each of the traversing boxes of a lever stop provided with four or more striking faces, a second stop provided with two striking faces, thread carrier bars, tappets on the thread carrier bars, a bar for raising and lowering the stops, carried by arms on a rocking shaft, a lever which is adjusted by studs on a pattern chain and is connected to an arm on the rocking shaft for the purpose of rocking the latter from time to time and adjusting the lever stops, substantially as described.
